VALVED AERATION DEVICE

Thorwald H. Hansen, Rahway, N. J.

Application September 21, 1951, Serial No. 247,619

7 Claims. (Cl. 210—16)

The present invention is directed to a device adapted to be used in conjunction with aquaria and in other fields, particularly in aquaria of larger sizes used by private individuals.

The device is specially designed to aerate the aquaria and to filter the water therein to purify it. Such a device is described and claimed in my co-pending application Serial No. 205,351, filed January 10, 1951, now Patent No. 2,614,529, and entitled "Filter Aerator for Aquaria." The mechanism there described has been found in practice to be eminently satisfactory for the intended purpose and it has found a considerable use in the field. The present invention is an extension of the invention of the aforesaid application for patent and includes improvements therein whereby more uniform and more vigorous aeration of the aquaria is obtained without any additional equipment or any increase in size of the air pump. The present invention also contemplates the provision of a valve which may be used to increase the effectiveness of the device.

In view of the above it is among the objects of the present invention to provide a filtering and aerating device for a tank, aquarium or the like, which is simple in construction and which may be readily altered in size and arrangement to fit into tanks of various sizes and depths.

It is also among the objects of the present invention to provide a device of the character described, wherein an air lift arrangement is provided such that the lift is in a plurality of steps, whereby the amount of water filtered and aerated is increased.

It is further among the objects of the present invention to provide a valve arrangement which is used to control the flow of air or liquid and which may be adjusted quite simply without the necessity of valve handles or threaded or rotating parts.

It is still further among the objects of the present invention to provide means whereby the aerating device may at desired times be used as a means for removing deposits or suspended matter from the tank or aquarium and thus maintain the water in a pure state.

In the accompanying drawing constituting a part hereof and in which like reference characters indicate like parts,

Fig. 1 is a front elevational view of an aerating and filtering device made in accordance with the present invention, some parts being shown broken away for clearness;

Fig. 2 is a horizontal cross-sectional view thereof taken along line 2—2 of Fig. 1;

Fig. 3 is a vertical cross-sectional fragmentary view showing the specially constructed valve embodied in the device;

Fig. 4 is an elevational view similar to Fig. 3, some parts being broken away and taken at about 90° to the view of Fig. 3, and

Fig. 5 is a vertical cross-sectional fragmentary view showing the nature of the air inlets into the device.

There is provided a tank or aquarium 1 having sand or gravel 2 in the bottom thereof and filled with water 3

2

up to point 4. An inverted cup 5 partly embedded within gravel 2 and a hollow neck 6 thereon is fitted into sleeve 7. A tube 8 has its lower end fitted in sleeve 7 and its upper end in sleeve 7'. From the top of sleeve 7' a tube 9 extends to any desired point. Sometimes said tube terminates at 10 below level 4, at other times above said level, and if desired it may have a gooseneck at the upper end thereof. These variations are dependent upon the conditions which the user desires in the aquarium.

10 A short tube 11 extends into sleeve 7 at an upward angle, as shown in Fig. 5. A short tube 12 vertically placed connects into the tube and an air duct or pipe 13 is inserted in the open end of tube 12. A plug 14 having a bevelled inner face 15 is inserted in tube 11. By twisting plug 14 into various positions the opening from tube 12 to tube 11 may be changed to suit conditions.

15 A horizontal chamber 16 closed at the ends has pipes 17 and 17' extending downwardly therefrom. Pipe 17 extends into connecting sleeve 15 having a valve therein which is described below. Extending upwardly from chamber 16 is a pipe 18 entering sleeve 19, which in turn is connected to pipe 20 and to a source of air under suitable pressure. Tube 13 is attached to tube 9 by a suitable clamping arrangement 14'.

20 Tube 17' is inserted in connecting sleeve 15', into the lower end of which extends the upper end of tube 13'. This in turn is secured to tube 8 by clamping means 14'. The structure of tube 7 is identical with that shown in Fig. 5 where upwardly extending duct 11' is the equivalent of duct 11 and vertical tube 12' is identical with tube 12.

25 With reference to Figs. 3 and 4 the valve arrangements in sleeves 15 and 15' are identical. A nipple 21 is interposed between sleeve 15 and pipe 13 and it has a flat seat 22 at the inner end thereof. A flat washer 23 of resilient material may be placed on face 22 and act as a seat for the valve. In some cases washer 23 may be omitted and face 22 may be the valve seat.

30 A second nipple 24 is interposed at the opposite end of sleeve 15 between the same and pipe 17, the lower end of which constitutes the valve. Said lower end is closed and is conical in form, as shown at 25. An opening 26 in the side of tube 17 adjacent to end 25 thereof, here shown as triangular in shape, provides means for flow of fluid through pipes 13 and 17 when the valve is opened.

35 In order to manipulate the valve sleeve 15 is grasped with one hand and tube 17 with the other. The elements are usually made of synthetic plastic material and while they fit sufficiently tightly to be fluid-tight, the inherent resiliency thereof allows relative movement thereof under stress. If the valve is open, as shown at Fig. 3, and it is desired to close the same, tube 17 is gently twisted with a downward pressure whereby valve 25 seats on washer 23 and cuts off the flow of fluid. The valve need not be completely closed but may be adjusted in a number of intermediate positions whereby control of the volume of flow is obtained.

40 In the normal use of the device valves 25 are open and plug 14 is in the position shown in Fig. 5. Air is forced under suitable pressure through tube 13 whereby air enters sleeve 7 and raises water upwardly through pipe 8. Filtration of the water takes place through the gravel adjacent to cup 5. Simultaneously air forced through tube 13' enters sleeve 7' and assists in forcing water upwardly through pipe 9 and out through end 10 thereof. By this means a greater flow of water is obtained with more effective aeration thereof.

45 At times it is desirable to clean out of the tank sediment which accumulates at the bottom thereof or is distributed throughout the water contained in the tank. In such case there is provided a chamber 27 which is rela-

tively large in diameter and open at both ends. A series of projections 28 are provided at the lower end of said chamber. A filter cloth 29 in the form of a bag having an elastic 30 at the mouth thereof is placed over the end of chamber 27 with the elastic 30 above projections 28. This insures that there will be no accidental slipping off of filter 29. At an intermediate point in the side of chamber 27 is an elbow 31 which is used into the side of the chamber at an angle so as to cause a tangential flow of liquid during the operation. Cap 32 is secured to the top of chamber 27 and an opening 33 therein prevents the formation of air locks.

When it is desired to clean the suspended matter from the water, elbow 31 is connected to end 10 of pipe 9. The entire device is held in the hand and with or without cup 5, is moved over the surface of the gravel 2 whereby water and sediment are drawn into pipes 8 and 9 and forced tangentially into chamber 27 which is held at least partly above the liquid level. Thereby the water so moving passes through filter 29, depositing the sediment therein. Similarly the device may be used to catch and remove foreign matter which may be floating in the body of the water or even at the surface thereof. After the cleaning operation is completed, chamber 27 is removed and the device again set in position for normal functioning. The chamber may be easily cleaned by removing the filter and flushing the interior thereof. The filter may then be replaced for a further operation.

Water tube sizes may be changed to allow for increased flow of water in any number of stages, as for example, pipe 9 may be of larger diameter than pipe 8. The lower end of air duct 13 is notched and bevelled so that by twisting the same in various positions, the size of air bubble may be altered and plug 14 may be similarly twisted for the same purpose. Valve 25 may be of different shape, as for example, it may be flat, rounded or the like. In place of the filter cloth 29 other means to accomplish the same result may be provided, as for instance, a removable cap similar to 32 filled with cotton or glass wool may be slipped over the bottom of chamber 27. The angle of tube 11 may be changed at will and it may enter sleeve 7 at various angles even at approximately a right angle.

While valve 25 is adjustable it may be permanently locked in position after suitable adjustment by use of a solvent or a cement which fuses the material of the several parts to make them integral. Any suitable plastic material may be used for the several elements but usually it is preferred to have a transparent synthetic resin which is used for most or all of the parts of the device. The valve may be incorporated in various other elements such as a T-shape tube or a cross or any other combination of tubes. Such valves are very light and when embodied in an aquarium they do not tend to pull down on the connecting poles, thus avoiding pinching off the flow of fluid.

The valve may be applied to other uses as desired and may be made of metal suitable for the purposes. These and other changes in the details of construction may be made within the spirit of the invention, which is to be broadly construed and not to be limited except by the character of the claims appended hereto.

I claim:

1. In an aeration device for tanks, a pipe adapted to extend below the level of liquid in said tank, an air tube extending along said pipe and entering the same at an upward angle below said level, a second air tube extending along said pipe and entering the same at an upward angle at a different level, an air chamber above said pipe, both of said air tubes being fixed to said chamber, said chamber being connected to a single source of air under pressure.

2. In an aeration device for tanks, a pipe adapted to extend below the level of liquid in said tank, an air tube extending along said pipe and entering the same at an upward angle below said level, a second air tube extend-

ing along said pipe and entering the same at an upward angle at a different level, an air chamber above said pipe, both of said air tubes being fixed to said chamber, said chamber being connected to a single source of air under pressure, and a valve in at least one of said air tubes.

3. In an aeration device for tanks, a pipe adapted to extend below the level of liquid in said tank, an air tube extending along said pipe and entering the same at an upward angle below said level, a second air tube extending along said pipe and entering the same at an upward angle at a different level, an air chamber above said pipe, both of said air tubes being fixed to said chamber, said chamber being connected to a single source of air under pressure, and a valve in at least one of said air tubes, said valve including a seat in said tube, a hollow valve integral with a second tube and having at one end a complementary seat and a side opening adjacent said end, said second tube being longitudinally slideable with respect to said seat.

4. In an aeration device for tanks, a pipe adapted to extend below the level of liquid in said tank, an air tube extending along said pipe and entering the same at an upward angle below said level, a second air tube extending along said pipe and entering the same at an upward angle at a different level, an air chamber above said pipe, both of said air tubes being fixed to said chamber, said chamber being connected to a single source of air under pressure, and a valve in at least one of said air tubes, said valve including a seat in said tube, a hollow valve integral with a second tube and having at one end a complementary seat and a side opening adjacent said end, said second tube being longitudinally slideable with respect to said seat, the opposite end of said valve being connected to said tube for allowing flow of fluid therethrough.

5. In an aeration device for tanks, a pipe adapted to extend below the level of liquid in said tank, an air tube extending along said pipe and entering the same at an upward angle below said level, a second air tube extending along said pipe and entering the same at an upward angle at a different level, an air chamber above said pipe, both of said air tubes being fixed to said chamber, said chamber being connected to a single source of air under pressure, and a valve in at least one of said air tubes, said valve including a seat in said tube, a hollow valve integral with a second tube and having at one end a complementary seat and a side opening adjacent said end, said second tube being longitudinally slideable with respect to said seat, and a resilient washer on said tube seat.

6. In an aeration device for tanks, a vertical pipe adapted to extend below the level of liquid in said tank, an air tube extending along the outside of and adjacent to said pipe and entering the same at an upward angle below said level, an elongated chamber having an opening at the bottom, a filter in said opening adjacent to said pipe and extending below said liquid level, an elbow tube on said chamber, said elbow tube fitted onto the upper part of said pipe and supported thereby, said chamber being supported by said pipe, and said chamber, pipe and tubes being jointed together as a unit.

7. In an aeration device for tanks, a vertical pipe adapted to extend below the level of liquid in said tank, an air tube extending along the outside of and adjacent to said pipe and entering the same at an upward angle below said level, an elongated chamber having an opening at the bottom, a filter in said opening adjacent to said pipe and extending below said liquid level, an elbow tube on said chamber, said elbow tube fitted onto the upper part of said pipe and supported thereby, said elbow tube being off-center to said chamber to impart a swirling motion to fluid passing into said chamber from said elbow tube, said chamber being supported by said pipe, and said chamber, pipe and tubes being jointed together as a unit.
